KNIFE OSCILLATING DEVICE

Edgar B. Kerst and Alpheus O. Hurxthal, Philadelphia, Pa., assignors to Proctor & Schwartz, Incorporated, Philadelphia, Pa., a Corporation of Pennsylvania

Application March 4, 1932. Serial No. 596,886

8 Claims. (Cl. 18—15)

This invention relates to devices arranged to chill and solidify plastic material, such as soap, in the form of a thin film or layer on a continuously moving carrying surface, such as the 5 peripheral surface of a chilling roll, where the material is finally scraped from the roll in the form of chips.

Heretofore it has been the practice to provide a stationary scraper having a more or less resilient contact with the carrying surface of the chilling roll and set at an angle with respect to the surface of the roll to scrape the material from the roll as the roll is rotated with respect to the scraper.

15 In devices of this kind when the film of material on the surface of the roll is exceptionally thin, such for example as about 5/1000ths of an inch in thickness, required by soap manufacturers at the present time in order that the soap chips 20 will dissolve instantly, the material, as it contacts with the scraper, has a tendency to back up on the surface of the roll, thereby increasing the thickness of the film substantially twice its 25 normal thickness before the material will chip off the surface of the roll.

One object of the present invention is to eliminate the backing up of the material and the consequent thickening of the chips as the material is removed from the roll.

30 The construction and operation of the mechanism forming the subject of the present invention will be fully disclosed hereinafter, reference being had to the accompanying drawings, of which:

35 Fig. 1 is a face view of a portion of a chilling roll with the mechanism of the present invention applied thereto;

Fig. 2 is the sectional elevation taken on the line 2—2, Fig. 1;

40 Fig. 3 is a view similar to Fig. 1, showing an alternative construction; and

Fig. 4 is a transverse sectional elevation taken on the line 4—4, Fig. 3.

45 In the accompanying drawings, the frame of the machine is illustrated at 1. The chilling roll is diagrammatically illustrated at 2 with a film of material *x* carried by and adhesively contacting with the peripheral surface 3 of the roll 2. The roll 2 is provided with trunnions 4 which 50 are rotatably mounted in suitable bearings carried by the side frames of the machine and not shown in the present drawings.

Secured to and projecting upwardly from the 55 side frames 1, 1 of the machine are brackets 5, 5, to which are rigidly secured bearings 6 and 7 re-

spectively. The bearings 6 and 7 are adapted to rotatably and slidably support trunnions 8 and 9 projecting respectively from the opposite ends of a blade carrier 10.

Secured to and projecting below the carrier 60 10 is the scraper blade 11, the weight of the carrier 10 disposed at the opposite sides of the axes of the trunnions 8 and 9 providing the necessary weight to rotate the trunnions 8 and 9 within their bearings and thereby press the blade 11 into 65 scraping contact with the peripheral surface 3 of the roll 2.

In the present instance the trunnion 8 is provided with a cam follower in the form of a roller 70 12, which is adapted to bear against a cam surface 13 arranged to move substantially with the carrying surface 2 of the roll 1. In the present instance, the cam surface 13 is formed on one side face of a cam wheel 14 which is rigidly secured to a shaft 15 that is rotatably mounted 75 in the bearing 6 below the trunnion 8 of the carrier 10.

Also secured to the shaft 15 in the present instance is a sprocket 16 which is operatively connected by means of a chain or belt 17 with a 80 sprocket 18 rigidly secured to one of the trunnions 4 of the roll 2, so that as the roll 2 is rotated the cam wheel 14 will be correspondingly rotated and through the cam surface 13 thereof and the cooperating cam follower 12 on the outer 85 end of the trunnion 8 of the carrier 10, said carrier with the scraping blade 11 will be moved in one direction transversely of the peripheral surface 3 of the roll 2 in opposition to a spring 19 confined within the bearing 7 in which the opposite trunnion 9 of the carrier 10 is mounted.

One end of the spring 19 bears against a collar 20 secured to the trunnion 9 while the opposite end of said spring bears against an abutment 21 confined within the bearing 7. The 90 abutment plate 21 is adjustable axially of the trunnion 9 and the bearing 7 by means of an adjusting screw 22 tapped into the outer end 23 of the bearing 7 and engaging the outer side of the abutment plate 21. The spring 19 is adapted to move the carrier 10 and the scraper 11 longitudinally and in a direction opposite to that provided by the cam 13 and the cam follower 12.

Moving the scraper blade 11 transversely of the peripheral surface 3 of the roll 2, as the roll 105 is rotated in the direction of the arrow in Fig. 2, provides a shearing action between the peripheral surface of the roll 2 and the relatively beveled edge of the blade 11, whereby the film *x* is sheared from the surface 3 of the roll 2, in place of 110

merely being scraped or pushed therefrom as provided by the non-reciprocating blade bearing against the material-carrying surface of the roll as in machines of the prior art.

5 Another advantage attained by the reciprocation of the blade 11 with respect to the constantly moving peripheral surface 3 of the roll 2 resides in a more or less self-sharpening of the blade 11. Relative reciprocation between the blade and the surface of the roll prevents the blade or the surface of the roll from being worn in local spots, such as occurs with the non-oscillating blade, due to unequal hardness in various portions of the blade or of the peripheral surface of the roll 15 with which the blade contacts.

In order to prevent excessive rotation of the blade carrier 10 that would possibly react to cause the blade 11 to jump or vibrate on the surface 3 of the roll 2, the trunnion may be provided 20 with a pin 25 arranged more or less loosely fitting and sliding in a groove or slot 26 formed in the bearing 6, such pin 25 having such a sliding fit in the slot 26 as to permit slight rotation of the carrier 10 to press the blade 11 resiliently 25 against the surface 3 of the roll 2 but preventing a reacting rotation of the carrier 10 that would cause the blade 11 to be moved out of cooperating relation with respect to the surface 3 of the roll 2. This limiting of the rotation of the carrier 30 10 and consequently the trunnion 8 thereof is desirable to keep the roller 12 in correct operative engagement with the cam surface 13.

In the alternative construction shown in Figs. 3 and 4 the blade 111 is clamped in the carrier 110 by means of a clamp plate 30 secured to the carrier 110 by means of bolts 31. The carrier is provided at one end with a trunnion 109 rotatably and slidably mounted in a bearing 107. The opposite end of the carrier 110 is rotatably mounted on one end of a shaft 108 which is slidably mounted in a bearing 106 and prevented from rotating in said bearing by means of a key 125, the opposite end of the shaft 108 being provided with a cam roller 112 riding between and adapted to be engaged at diametrically opposed points by substantially parallel cam surfaces 113 of a cam element 114. The cam element 114 is rotatably mounted on a stud shaft 115 rigidly attached to and projecting from one side of the bearing 106.

On the hub 114a of the cam element 114 is a sprocket 116 by which the cam 114 is rotated, the cam element being held against axial movement with respect to the stud 115 by the collars 35 and 36 rigidly secured to the shaft 115.

Rotation of the cam 114 will cause positive axial reciprocation of the shaft 108 and consequently a corresponding reciprocation of the carrier 110 and blade 111 transversely of the peripheral surface 3 of the chilling roll 2. For this purpose and in order to permit free rotation of the carrier 110 with respect to the shaft 108 the said carrier is provided with a bearing 40 into which projects and freely rotates the one end 41 of the shaft 108, said shaft having an axially aligned reduced portion 42 passing through an opening 43 formed in an end wall 44 of the bearing 40 and provided outside the said wall with a collar 45, whereby longitudinal reciprocation of the shaft 108 will be transmitted to the carrier 110, at the same time permitting the carrier 110 to rotate freely about the shaft 108 while said shaft is held against such rotation by the key 125 co-acting with a correspondingly formed groove 126 in the bearing 106. By this mechanism the spring 19 in the bearing

7, which is arranged to move the carrier 10 in a direction opposite to that in which the carrier is moved by the cam surface 13, is eliminated and the blade carrier and the blade are moved positively in both directions by the action of the cam surfaces 113, 113.

We claim:

1. The combination of a roll having a peripheral surface arranged to carry a layer of material on and in adhesive contact therewith, a scraper extending across and in contact with the carrying face of the roll, means for reciprocating the scraper longitudinally and relative to said carrying face to remove the material therefrom comprising a cam surface movable with the carrying surface, a cam follower cooperating with the said cam surface and operatively connected to the scraper to move the scraper in one direction, and resilient means for moving the scraper in an opposite direction.

2. The combination of a roll having a peripheral surface arranged to carry a layer of material on and in adhesive contact therewith, a knife blade extending across and in contact with the carrying face of the roll, a carrier for said blade, a trunnion at each end of said carrier, for rotatably and slidably supporting said carrier, a cam adjacent one side of said roll and rotatable therewith, a cam follower cooperating with said cam and operatively connected to said carrier for moving the blade longitudinally and relative to the carrying face of the roll, and means for rotating the carrier about the axes of said trunnions to press the blade against the carrying face of the roll under predetermined pressure.

3. The combination of a roll having a peripheral surface arranged to carry a layer of material on and in adhesive contact therewith, a knife blade extending across and in contact with the carrying face of the roll, a carrier for said blade, a trunnion at each end of said carrier, a bearing for rotatably and slidably supporting each trunnion, a cam adjacent one side of the roll and rotatable therewith, a cam follower cooperating with said cam and operatively connected to one of said trunnions to move the carrier and the blade in one direction longitudinally of the blade, and resilient means cooperating with the other of said trunnions for moving the carrier and the blade in an opposite longitudinal direction.

4. The combination of a roll having a peripheral surface arranged to carry a layer of material on and in adhesive contact therewith, a knife blade extending across and in contact with the carrying face of the roll, a carrier for said blade, a trunnion at each end of said carrier, a bearing for rotatably and slidably supporting each trunnion, a cam adjacent one side of the roll and rotatable therewith, a cam follower cooperating with said cam and operatively connected to one of said trunnions to move the carrier and the blade in one direction longitudinally of the blade, and resilient means cooperating with the other of said trunnions for moving the carrier and the blade in an opposite longitudinal direction and comprising a spring confined in the bearing for the last said trunnion between an abutment on the trunnion and an abutment in the bearing.

5. The combination of a roll having a peripheral surface arranged to carry a layer of material on and in adhesive contact therewith, a knife blade extending across and in contact with the carrying face of the roll, a carrier for said blade, a trunnion at each end of the carrier, a bearing

for rotatably and slidably supporting each trunnion, a cam follower carried by and on the end of one of said trunnions, a cam cooperating with said cam follower to move the carrier and the 5 blade longitudinally and relative to the carrying face of the roll, and a weight on the carrier tending to rotate the carrier and the blade about the axes of said trunnions to press the blade against the carrying face of the roll under predeterminal 10 pressure.

6. The combination of a roll having a peripheral surface arranged to carry a layer of material on and in adhesive contact therewith, a knife blade extending across and in contact with the 15 carrying face of the roll, a carrier for said blade, a trunnion at each end of the carrier, a bearing for rotatably and slidably supporting each trunnion, a cam follower carried by and on the end of one of said trunnions, a cam co- 20 operating with said cam follower to move the carrier and the blade longitudinally and relative to the carrying face of the roll in one direction, and resilient means cooperating with the other of said trunnions to move the blade and its carrier in the opposite direction.

7. The combination of a roll having a peripheral surface arranged to carry a layer of material on and in adhesive contact therewith, a knife blade extending across and in contact with the 25 carrying face of the roll, a carrier for said blade, a trunnion at each end of the carrier, a bearing

for rotatably and slidably supporting each trunnion, a cam follower carried by and on the end of one of said trunnions, a cam cooperating with said cam follower to move the carrier and the blade longitudinally and relative to the carrying face of the roll in one direction, resilient means cooperating with the other of said trunnions to move the blade and its carrier in the opposite direction, and a weight on the carrier tending to rotate the carrier and the blade about the axes of said trunnions to press the blade against the carrying face of the roll under predeterminal 80 pressure.

8. The combination of a roll having a peripheral surface arranged to carry a layer of material on and in adhesive contact therewith, a knife blade extending across and in contact with the carrying face of the roll, a carrier for said blade, a trunnion at each end of said carrier, a bearing for slidably supporting each trunnion, a cam follower on one of said trunnions, a double faced cam acting against opposed points on said cam follower to reciprocate the carrier and the blade longitudinally of and relative to said carrying face, means for preventing rotation of the follower carrying trunnion, and means for permitting rotation of the blade carrier relative to the last said trunnion.
